FRANK J. CONDIT, OF MILWAUKEE, AND EDWIN L. SMALLIE, OF WHITEFISH BAY, WISCONSIN, ASSIGNORS TO HEVI DUTY ELECTRIC COMPANY, OF MILWAUKEE, WISCONSIN, A CORPORATION OF WISCONSIN

ROTARY RETORT FURNACE

Application filed April 3, 1930. Serial No. 442,591.

Our invention relates broadly to rotary retort furnaces and more particularly to a construction of bearing support for a revolving retort in a rotary retort furnace.

5 One of the objects of our invention is to provide a construction of support for a rotatable retort in a rotary retort furnace, wherein the movement of the retort may be maintained at an extremely slow rate while 10 preventing the warpage or distortion of the retort under the load.

Another object of our invention is to provide a construction of support for a rotary retort within the furnace intermediate the 15 end bearing for the retort for preventing distortion of the retort under load conditions.

Still another object of our invention is to provide a construction of intermediate support for a revolvable retort where the support may be adjusted to reduce the tendency 20 of warpage or distortion in the retort under the action of the load and to compensate for irregularities in the surface of the retort.

25 A further object of our invention is to provide a construction of intermediate support for a rotary retort in which a roller directly contacts with the exterior surface of the retort, with means for elevating or lowering the roller member for properly adjusting the intermediate support with respect to the rotary retort for relieving the strain upon the retort intermediate the ends thereof under loaded conditions.

30 A still further object of our invention is to provide a construction of intermediate adjustable support arranged in a position between the end bearings of the retort and adjustable from the exterior of the retort furnace for properly engaging the retort intermediate the ends thereof.

Still another object of our invention is to provide adjusting means for mounting a rotating retort in which reciprocating supporting means are actuated laterally with respect 5 to the axis of the rotating retort for permitting expansion of the retort when in its heated condition.

Other and further objects of our invention reside in the construction of bearing support for a revolving retort, as set forth more fully

in the specification hereinafter following by reference to the accompanying drawings in which:

Figure 1 is a side elevation partially broken away showing the interior of the rotary retort and the arrangement of the adjustable bearing in the retort furnace in accordance with our invention; Fig. 2 is a view of the retort furnace partially in end elevation and partially in cross-section showing the adjustable bearing support arranged according to our invention; Fig. 3 is an enlarged side elevation of one of the intermediate supports for the rotary retort illustrated in Figs. 1 and 2; Fig. 4 is an end elevation of the intermediate support for the rotary retort furnace illustrated in Figs. 1 and 2; Fig. 5 is a longitudinal cross-sectional view taken through the intermediate support; Fig. 6 is a plan view of the bed plate which supports the adjustable bearing for properly centering the rotary retort in accordance with our invention; Fig. 7 is a cross-sectional view through the bed plate shown in Fig. 6 on line 7-7 thereof; Fig. 8 is a lateral cross-sectional view through the bed plate illustrated in Fig. 6 taken on line 8-8 thereof; Fig. 9 is a plan view of the lever which is adjustably mounted with respect to the bed plate 23; Fig. 10 is a cross-sectional view through the lever on line 10-10 of Fig. 9; Fig. 11 is a lateral cross-sectional view through the lever of Fig. 10 on line 11-11 thereof; Fig. 12 is a cross-sectional view through the adjustable lever on line 12-12 of Fig. 10; Fig. 13 is a plan view of the yoke which carries the roller members and which engage the sides of the retort; Fig. 14 is a side elevation of the yoke illustrated in Fig. 13; and Fig. 15 illustrates an arrangement of multiple adjustable means for centering the rotary retort.

It has heretofore been the practice in constructing furnaces of the retort type to have rolling supports located only beyond the heads of the furnace, thus leaving a considerable length of the retort unsupported. Such structures have required that the retort be continuously revolved until a visible temperature disappeared in order to prevent distortion of the retort by warpage. This causes

a waste of time and power used after the actual performance of work has ceased. Furthermore, it has been found in practice that furnaces constructed in accordance with prior practice and having the retort filled or partially filled, four was the lowest number of revolutions per hour without resulting distortion to the retort. Four revolutions per hour, as a general rule, would cause such a tumbling action of parts in the retort as to cause damage to any sharp edges of finished parts, such as threads of cap screws, bolts, set screws, etc.

In a rotary retort furnace the retort when loaded must be rotated at that rate of speed which will prevent injury to the load under heat treatment within the retort and at the same time a sufficient rate of speed maintained which will avoid warping or distortion of the retort under conditions of high temperature.

Within the rotary retort furnace of our invention we provide intermediate adjustable supports along the length of the retort for relieving the strain upon the retort as it is rotated at high temperature and enabling the retort to be revolved at a relatively slow rate of speed to avoid injury to the load within the retort. Heretofore when revolving a retort through a relatively large number of revolutions per hour, the parts under heat treatment tend to rub one with respect to another, and if this abrading or rubbing action becomes too great, damage to fine screw threads or sharp edged parts may result. In the rotary retort furnace of our invention having adjustable means intermediate the end bearings thereof for supporting the loaded retort, the rate at which the retort is revolved may be maintained very low and yet distortion and strain upon the walls of the retort substantially eliminated and injury of the parts abrading each other practically prevented.

Referring to the drawings in detail, reference character 1 designates a furnace chamber surrounded by ceramic refractories 2 contained in the furnace shell 3, having end heads 4. Furnace chamber 1 may be heated by any suitable means but is shown heated by electrical elements 5. Reference character 6 designates a cylindrical retort having outer end heads 7 to which is attached an inner head 8. The inner and outer heads may be connected by any suitable means such as pipe 9 and tie rods 9a. Pipe 9 affords a means for a gas connection when gas must be used for such purposes as preventing oxidization or causing carburization of parts in the retort. For the latter use it is sometimes found advisable to carry the retort temperature up to 1650° F. to 1750° F., at which temperatures the non-oxidizing cast metal, such as nickel-chromium composition, loses considerable of its stability as to original

form. Reference character 10 indicates a suitable clamping device to hold head 7 tight against the opposite end of retort 6. Reference character 11 indicates a motor driven train of gears enclosed in a suitable housing 70 to impart a relatively low number of revolutions per minute to shaft 12 on which is a sprocket 13 connected to sprocket 14 or drum by means of sprocket chain 15. Reference character 16 denotes an idler sprocket on shaft 17 having hub 18 and lever 19. Lever 19 has a helical coil 20 under tension to keep idler 16 constantly in engagement with the slack side of chain 15. At 21 we have shown a roller having trunnions 21a in a pivotal yoke 22 and angularly movable on shaft 41 which is retained in position by retaining pins 41a. Yoke 22 has hub bearing 21c in close relationship to lugs 40, which are part of lever 38 mounted at one end on a rounded knife-edge bearing 37 which is supported as part of bed plate 23a. The bed plate is aligned in one direction by means of depending flange 23b engaged in the brick work of the furnace and laterally by means of the ceramic refractory walls as shown in Fig. 1. Lever 38 which is shown more clearly in Figs. 9, 10, 11 and 12, has two finger-like projections 38a one on each side of lever 33 to form an alignment means. On the opposite end of the lever 38 there are two angularly disposed limiting flanges 39 to hold lever 38 on knife-edge 37. 39a is a rib centrally connecting flanges 39 and lodged in a slot 37a in the knife edge 37 to prevent lateral dislodgement of lever 38.

In Fig. 3 reference character 42 shows a cam having trunnions 42a retained by lugs 23 on the bed plate 23a. Cam 42 is shown as having an angularly projecting lever 33 extending between the forks of clevis 34 and mounted therein by means of pin 35, the pins being retained by studs 35a. The clevis 34 is formed as part of an adjustable rod 36 adjustable by nuts 36a engaging the bottom or external portion of furnace shell 3.

As will be understood from the drawings the yoke 22 with rollers 21 may be elevated to near relationship to the outside of the retort. It will also be noted that if the radius 115 of the retort opposite one roller is greater than the radius of the retort opposite the second roller, the yoke 22 having rollers 21, will revolve about pin 41 to compensate for the difference in such radii or for irregularities on the outer surface of the retort.

While only one immediate support is shown in Fig. 1, we preferably use two intermediate supports located equidistant from the longitudinal vertical center line of the furnace, or 12 we may use three or more supports.

The retort furnace is shown mounted on an underslung frame 24 supported by stands 25, permitting the tilting of the retort for loading and discharging. On one stand 25 there

is a bracket 25a supporting a bearing for the shaft of hand wheel 30a. On such shaft 30 is mounted a bevel pinion 29 engaging bevel gear 28 which is attached to screw 27 engaged in pivotally mounted nut 26. Movement of thread 27 draws nut 26 to or away from hand wheel 30a. Nut 26 is supported by bracket 26a, which in turn is attached to a roller quadrant behind guard plates 25b, the guard plates being advisable on account of the quadrant rolling on a rack of frame 25. Two flanges 32 on the retort spanning one wheel 31 keep the retort from sliding when the furnace is tilted.

15 Instead of the cam lifting device of Fig. 3 causing an upward or rolling motion to yoke 22, a similar device might be used to adjust a single roller such as might be mounted directly on shaft 41 as shown in Fig. 15. In such instance two such lifting devices are used in the assembly shown in Fig. 15.

20 In the double lift arrangement we provide two lever members of identical construction shown at 50 mounted upon two bed plates 23a, similar to the bed plate construction illustrated more particularly in Figs. 6, 7 and 8. The bed plates are mounted on either side of a center line passing through the axis of the retort 6 and the adjusting rods 36 thereof extend through the furnace wall 2 and are adjustable by means of nuts 36a in a manner as has heretofore been described with respect to the single lift. The levers 50 differ from the construction of the lever 38, to the extent that lugs 52 project upwardly from levers 50 and provide bearings for shaft member 54a which are pinned in position with respect thereto by means of pins 54b.

25 A roller 54 is carried upon each shaft member 54a and by virtue of the opposed relation of the two lifts, the rollers 54 support the retort from opposite sides of the center line thereof. By adjusting the position of one or the other rod members 36 either roller 54 may be brought into position to properly guide the retort in its rotary movement.

30 In order to observe the movement of the rotary retort, we provide a peep-hole in one end of the furnace through which the effect of adjustments of the several lifts may be checked. Adjustments must be made at the several points of support of the roller members with respect to the rotary retort, and in 35 the instance of the double lift construction, adjustments must be made on both of the lifts to properly balance the operation of the retort.

35 Rotary retort furnaces embodying the principles of our invention have been found to be highly successful and practical in operation. In a furnace having a retort of 14 inches inside diameter and approximately 10 feet in length between the positions of the outer roller supports represented at 31 in

Fig. 1 of the drawings, we have operated the retort continuously over the regular night period factory shut-down without distortion of the retort while carrying a charge of 1,000 pounds and with the furnace maintained at 70 a temperature of 1700° F. This results in a saving of power and attendance which would be lost by the requirement of keeping the retort revolving until an invisible temperature was attained in the retort. 75

80 Furthermore, we have ascertained that revolving the same described retort one or one-half revolutions per hour with the retort heated to 1700° F. and containing a charge of set screws being case hardened, no damage was caused to the threads of the screws. This brings the rotary retort furnace in a field for carburizing sharp edged parts, which has not heretofore been successfully accomplished by any other furnace of the retort type. The rotation of the retort is maintained at less than two revolutions per hour and yet strain and distortion upon the retort are substantially prevented, while the injurious abrasion of parts one with respect 85 to another is avoided during the rotative movement.

90 While we have described our invention in certain preferred embodiments, we desire that it be understood that modifications may be made and that no limitations upon our invention are intended other than those imposed by the scope of the appended claims.

95 What we claim as new and desire to secure by Letters Patent of the United States is as follows:

100 1. In a rotary retort furnace, a furnace chamber, a rotary retort, means supported by said furnace for journaling said rotary retort adjacent opposite ends thereof, and 105 roller members mounted intermediate the ends of said retort and disposed wholly within said furnace chamber, said roller members being vertically adjustable from the exterior of said furnace chamber for engaging 110 said rotary retort and supporting said retort when said retort is in operative position.

115 2. In a furnace structure, a furnace chamber and a longitudinally extending retort, means for journaling opposite ends of said retort for rotary movement within said chamber, and a plurality of means positioned wholly within the furnace chamber and engaging the exterior walls of said retort for supporting said retort for rotary movement 120 thereof under conditions of load, and means below said chamber for adjusting said means with respect to said retort.

125 3. A support for a rotatable retort comprising means mounted beneath the rotatable retort, a lever member supported by said means, a roller member carried by said lever member and operating in engagement with the exterior wall of said retort, a cam mounted upon said means and engageable with 130

- 5 said lever member, and means for angularly shifting said cam for moving said lever member and correspondingly adjusting the position of said roller with respect to said retort.
- 10 4. Supporting means for a rotatable retort comprising a supporting plate member, a fulcrum on said supporting plate member, a lever positioned upon said fulcrum, a roller member carried by said lever and engaging said rotatable retort, and a cam journaled with respect to said supporting means, said cam being angularly shiftable for raising or lowering said lever for correspondingly adjusting the position of said roller member with respect to said rotatable retort.
- 15 5. A support for a rotatable retort comprising a supporting plate, a lever member fulcrumed with respect to said supporting plate, a roller member carried by said lever member and engageable with the exterior surface of said retort, a cam journaled with respect to said support in a position between the ends of said lever member remote from the fulcrum thereof, and means for angularly shifting the position of said lever member for correspondingly changing the position of said roller member with respect to the exterior surface of said rotatable retort.
- 20 30 6. Supporting means for a rotary retort comprising a supporting plate having an upwardly protruding portion adjacent one end thereof, a lever member having a pair of downwardly projecting portions adjacent one end thereof, the downwardly projecting portions of said lever member embracing the upwardly protruding portion of said plate for providing a fulcrum for said lever member, a cam journaled in said supporting means adjacent the under surface of said lever member, means for angularly shifting said cam for adjusting the position of said lever member, and a roller journaled with respect to said lever member, said roller engaging said rotary retort for supporting said retort in accordance with the corresponding angular movement of said cam.
- 25 40 50 7. Supporting means for a rotatable retort comprising a base plate, a lever fulcrumed with respect to said base plate, a cam beneath said lever and journaled with respect to said base plate, means for adjusting the angular position of said cam with respect to said lever for shifting said lever about the fulcrum thereof, and a roller member carried by said lever, said roller member engaging the exterior surface of a rotatable retort for supporting said retort in accordance with the adjustment in position of said cam.
- 55 60 65 8. Supporting means for a rotatable retort comprising a supporting plate, an upwardly protruding member adjacent one end of said plate, a lever fulcrumed adjacent one end thereof on said upwardly protruding member, a cam journaled with respect to said

supporting plate in a position substantially beneath the opposite end of said lever, a yoke pivotally mounted upon said lever, and a plurality of roller members journaled in said yoke and rotatably engaging said rotatable retort, said roller members being shiftable in position in accordance with changes in the angular position of said cam beneath said lever.

9. In a support for a rotatable retort, a supporting plate, an upwardly protruding member adjacent one end of said supporting plate, an angularly shiftable cam journaled with respect to said supporting plate, a lever member having a pair of downwardly extending angular portions adjacent one end thereof embracing the upwardly protruding portion of said supporting plate for providing a fulcrum for said lever member, the opposite end of said lever member substantially embracing said angularly shiftable cam, means for adjusting the angular relation of said cam with respect to said lever member for raising or lowering said lever member, and a multiplicity of roller members supported with respect to said lever member for engaging the exterior walls of a rotatable retort on opposite sides of the central axis thereof.

10. In a rotary retort furnace, a heat treatment chamber, a rotatable retort extending through said chamber and journaled adjacent opposite ends thereof, supporting means intermediate the journaled ends of said retort comprising supporting plate members located beneath said retort on opposite sides of the central axis thereof, lever members fulcrumed adjacent the ends of said supporting means remote from the central axis of said retort and extending laterally toward the central axis thereof, a roller member carried by each of said lever members and engageable with the exterior of said retort, and adjustable cam devices located between said supporting means and each of said lever members substantially beneath said roller members for angularly shifting the position of said lever members on either side of the central axis of said retort for relieving the strain upon said retort intermediate the ends thereof under conditions of load and high temperature.

In testimony whereof we affix our signatures:

FRANK J. CONDIT.
EDWIN L. SMALLEY.
